LOOM STOP MOTION

Jérôme Lachapelle, St. Joseph, Quebec, Canada,
assignor to Drummondville Cotton Company
Limited, Montreal, Quebec, Canada, a corpora-
tion of Canada

Application February 20, 1952, Serial No. 272,554

4 Claims. (Cl. 139—340)

1

The present invention relates to improvements in textile looms and more particularly to a means for automatically stopping a loom when the cloth roll has been filled to a predetermined amount.

During the weaving process, textiles are normally woven in a continuous length but are removed from the loom in shorter lengths or "cuts." These "cuts" are usually maintained at a length suitable for inspection and subsequent shipping to the customer. Usually, provision, in the form of a warp measuring motion, is made at the slasher for indicating the length of a "cut" on the warp yarns so that the operator of the loom will know when the end of a "cut" is near. When the portion of the cloth bearing the mark is wound on the cloth roller the loom is stopped and the cloth cut at the mark and removed from the loom. As will be appreciated, this means that the operator must watch the run of each loom fairly closely at the end of each "cut" so as to be able to stop the loom at the required time.

The present invention aims to provide a means of automatically stopping a loom when a predetermined amount of cloth has been wound on the cloth roller.

Accordingly, the invention is a loom stop motion which, in combination, with the usual cloth roller, cloth roller mounting means, and the knock-off mechanism of the loom, provides a means of transmitting the movement of the cloth roller as the cloth builds up to the knock-off lever of the loom so as to pull it into stop position.

More specifically, in accordance with the present invention, the preferred means of transmitting the movement of the cloth roll shaft consists of an elongated flexible rod mounted in a flexible tube. Each end of the flexible tube is provided with an adjustable cylindrical terminal member and each end of the flexible rod is connected to a headed plunger slidably mounted in one of the cylindrical members. One of the plunger cylinder assemblies is mounted to the loom frame with the plunger head in the path of the cloth roller while the other assembly is mounted to the loom frame beneath and adjacent to a pivotally mounted knock-off member. The knock-off member is mounted on the loom frame so as to be capable of being pivoted into the path of the oscillating lay of the loom and is also pivotally connected to the knock-off lever of the loom. With this arrangement, depression of the first plunger, through contact with the cloth roll, slides the flexible rod through the flexible tube so as to extend the plunger at the other

2

end. The second plunger acts against the knock-off member placing it in the path of the lay so that the movement of the lay pushes the knock-off member and so pulls the interconnected knock-off lever into stop position.

As the plunger-cylinder assemblies are each adjustable as to the effective length of the plunger, the position where the plunger head comes in contact with the cloth roller can be predetermined so that the stopping action may take place at any predetermined position of the cloth roll relative to the amount of cloth wound on.

Having thus generally described the nature of the invention, particular reference will be made to the accompanying drawings, and in which:

Figure 1 is a diagrammatic view of a portion of a loom to illustrate certain parts associated with a preferred loom stop motion apparatus in accordance with the invention.

Figure 2 is an enlarged detail view of a portion of the cloth roll stand and cloth roller of the loom to show the roller mounting means and relative position of the stop motion actuating means.

Figure 3 is a diagrammatic view of the portion of the cloth roll stand and cloth roller shown in Figure 2 and also the knock-off arrangement of the loom to illustrate the relative positions of the plunger ends of the loom stopping apparatus when the cloth roll is filled to a predetermined amount.

Figure 4 is an enlarged detail view in section of one of the plunger assemblies showing the threaded engagement of the adjusting nut with the cylindrical member.

With particular reference to Figure 1 of the drawing a side elevation of a loom is shown diagrammatically to illustrate a preferred embodiment of a loom stop motion constructed in accordance with the present invention.

In this illustration 10 designates the frame of the loom, 12 designates the oscillating lay of the loom and 14 designates the cloth roll stand. The present apparatus is designed to transmit the downward movement of the cloth roller 16 on the stand 14 to a knock-off arrangement positioned in the path of the lay 12. The knock-off arrangement when engaged by the lay is adapted to pull the usual knock-off lever 18 into loom stopping position.

The knock-off arrangement shown consists of a knock-off bunt 20, secured to the lay 12, which is adapted to engage a knock-off member 22 when this member is raised. The knock-off member 22 is pivotally mounted to a knock-off link 24

pivotedly mounted on a knock-off stand 26 attached to the loom frame. A connecting rod 28 extends between the knock-off member 22 and the knock-off lever 18 so that forward motion of the member 22, under the influence of the lay 12, pulls the lever 18 into loom stopping position. This arrangement is in common use on many automatic looms and is designed primarily for use in combination with a warp stop motion actuated through breakage of warp threads.

In accordance with the present invention a bracket 30 is secured to the loom frame beneath the pivotedly mounted knock-off member 22 so as to support one end of a plunger cylinder arrangement so that a plunger head 32 is adapted to come in contact with and raise the member 22 into the path of the knock-off bunt 20 secured to the loom lay 12.

The plunger head 32 is secured to the end of a flexible rod 34 which is mounted for sliding movement in a flexible tube 36 in the manner of a Bowden cable arrangement. One end of the flexible tube 36 is secured to an adjusting nut 38 which is threadably engaged with a cylindrical member 40 mounted on the bracket 30. The end of the flexible rod 34 to which the plunger head 32 is attached extends through and considerably beyond the cylindrical member 40 forming a plunger portion 42.

The flexible tube 36 and flexible rod 34 extend along the machine to the cloth roll stand 14 where the other end of the tube 36 is adjustably connected by a nut 43 to a cylindrical member 44 mounted on a bracket 46. The bracket 46 is secured to the cloth roll stand 14 beneath the take-off slot 48 with the other end of the flexible rod 34 extending beyond the member 44 forming a plunger portion 50 having a plunger head 52. The cloth roll stand 14 is of a well known construction wherein the cloth roller 16 is supported on bearings 60 mounted for vertical sliding movement in a slot 62. The downward movement of the cloth roller 16 acts on a rack 64 which is in meshed engagement with a train of gears (not illustrated) which act against a spring loaded shaft adapted to control the winding on of the cloth.

With the present arrangement as the cloth roll builds up and the cloth roller 16 descends it reaches a predetermined point, preferably in alignment with the take-off slot 48, where it comes into engagement with the plunger head 52 depressing the plunger portion 50 within the cylindrical member 44 and causing a corresponding raising of the plunger head 32 so as to raise the knock-off member 22.

The effective length of the flexible rod 34 and consequently the extended amount of the plunger portions 42, 50 can be adjusted by the adjusting nuts, 38, 43. The location of the adjusting nuts 38, 43, due to their threaded engagement with the cylindrical members 40, 44 extends or shortens the overall combined length of the flexible tube 36 and the members 40, 44 and consequently the amount of the rod 34 extending beyond the cylindrical members 40, 44. This permits the stop motion to be adjusted to stop the loom to suit any desired amount of cloth wound on the cloth roller 16.

I claim:

1. In a loom having a cloth roll stand and a cloth roller slidably mounted for vertical descent on said stand as the cloth is wound on; a loom stop motion comprising the combination with loom stopping mechanism including a knock-off lever assembly adapted to actuate the knock-off lever of the loom into loom stopping position and having a pivotedly mounted member engageable by the loom lay when raised, and a flexible motion transmitting member between said cloth roll stand and said knock-off assembly whereby downward movement of said cloth roller is transmitted to cause upward movement of said pivotedly mounted knock-off lever assembly member.
2. A loom stop motion as claimed in claim 1 wherein said flexible motion transmitting member comprises a flexible cable slidably housed within a flexible tube and extending adjacent said cloth roll stand to adjacent said loom stopping assembly, one end of said flexible cable being in the path of said cloth roller and the other end being disposed beneath said pivotedly mounted knock-off member.
3. In a loom having a cloth roll stand and a cloth roller slidably mounted for vertical descent on said stand as the cloth is wound on; a loom stop motion comprising the combination with loom stopping mechanism including a knock-off lever assembly adapted to actuate the knock-off lever of the loom into loom stopping position and having a pivotedly mounted member connected to the loom knock-off lever and engageable by the lay of the loom when raised, and a flexible cable slidably housed in a flexible tube extending from the said cloth roll stand to adjacent said knock-off lever assembly, said tube being mounted at one end by adjustable means to a bracket secured to said cloth roll stand with the other end mounted by adjustable means to a bracket secured to the frame of said loom beneath said pivotedly mounted stop motion member, one end of said flexible cable extending beyond said flexible tube in the path of said cloth roller with the other end of said flexible cable extending beyond the other end of said flexible tube directly beneath said pivotedly mounted stop motion member, whereby downward movement of said cloth roller is transmitted to cause upward movement of said pivotedly mounted stop motion member raising it into the path of said loom lay.
4. A stop motion as claimed in claim 3 wherein said adjustable means comprise cylindrical members mounted on said tube supporting brackets and the ends of said flexible tube are connected to adjustable nuts threadably engaged with said cylindrical members.

JÉRÔME LACHAPELLE.
